UNITED STATES PATENT OFFICE.

WALTER D'ARCY RYAN, OF SCHENECTADY, NEW YORK.

HEADLIGHT.

Application filed March 12, 1926. Serial No. 94,191.

My invention relates to improvements in headlights and is particularly concerned, though not necessarily limited, to improvements in headlights for automotive vehicles.

5 The objects of my present invention are:

First, to provide a headlight that will produce a beam of considerable intensity or illuminating the roadway and objects at a considerable distance from the vehicle, in 10 combination with means for providing a less intense but adequate illumination of that portion of the roadway lying closer to the vehicle;

Second, to provide a headlight, such as 15 described, comprising means for effectively illuminating both sides of the road immediately adjacent the vehicle so as to enable the driver easily to perceive the curbs, ditches, road signs, etc.;

20 Third, to provide a headlight, of the character described, embodying means for illuminating crossroads in advance of the vehicle as it turns into such crossroads;

Fourth, to provide a headlight, such as 25 described, comprising means for producing an especially great intensity of illumination on the right side of the road so as to enable the driver more easily to perceive the curb and other similar obstacles even in misty or 30 foggy weather; and

Finally to provide a headlight, such as described, that is simple in construction and economical to manufacture.

Other objects of my invention will appear 35 as this description progresses, reference being had to the accompanying drawings, in which

40 Figure 1 is a vertical cross section through a headlight embodying one form of my invention;

Figure 2 is a transverse sectional detail on an enlarged scale;

Figure 3 is a front view of the reflector forming a part of the headlight; and

45 Figure 4 is a vertical section through the reflector.

Throughout the several views similar reference characters are used for referring to the same parts.

50 The embodiment of my invention disclosed herein comprises a suitable housing comprising the back 5 and the rather narrow side flange 6, both of which are integrally formed. A hollow stem 7, secured to the

55 lower portion of the back, provides means for introducing an electric cable, or cables,

not shown, for supplying current to the sources of light. A door ring 8 is pivotally mounted upon the flange 6 of the housing, by means of a suitable hinge 9, and is held in 60 closed position by means of a latch 10 that may be of any desired construction.

The reflector 11 may be of any suitable contour, paraboloidal, hyperboloidal, or it may have characteristics similar to the reflector described and claimed in my co-pending application, Serial No. 88,911, filed February 17, 1926, but in any event, the focal point, or focal region, of the reflector should lie well inside of the plane of the edge of the 70 reflector. The reflector is preferably provided with an integral, backwardly extending flange 12. A pivot pin 13, having a head 14, is secured to the flange on each side of the reflector and is pivotally mounted 75 upon a bracket 15 carried by the housing. One of these pivotal suspensions is shown in detail in Figure 2.

For adjusting the reflector about the axis 80 of the two pivot pins 13 I provide an adjusting screw 16 that extends through a suitable opening in the housing and is provided at its outer end with a suitable knob 17. This screw extends loosely through an opening in the downturned portion 18 of the bracket 85 19, that is soldered, or otherwise secured, to the flange 12, and engages a screwthreaded nut 20. A compression spring 21 is confined between the back of the housing and the downturned portion 18 of the bracket 19 and 90 tends to keep this portion of the bracket 19 in contact with the nut 20, whatever the position of the latter upon the screw may be. The nut 20 has a notch cut in its upper edge 95 for receiving the bracket 19 and the latter prevents rotation of the nut 20.

From the above description it will be seen that the reflector 11 can be tilted to any position corresponding to the position of the nut 20 on the screw 16 by merely rotating the 100 knob 17 in one direction or another.

The reflector 11 is provided with a lamp socket 22 for receiving the base of a suitable lamp 23, having the filament 24 that serves as the main source of light. This socket is 105 preferably located an appreciable distance below the axis 25 of the reflector, as shown in Figures 3 and 4.

The reflector is provided with a second socket 26, located close to the edge of the 110 reflector, for receiving a second lamp 27 having the filament 28 that forms a second,

- or auxiliary, source of light. The center of this socket is preferably located about ten degrees above a horizontal plane passing through the axis of the reflector, as shown in Figure 3, but this angle may be departed from to suit the particular use to which my headlight may be placed. It will be noted, from an inspection of the drawings, that the auxiliary source of light is positioned on the side of the axis of the headlight that is remote from the driver's side of the road. This will result in the reflection of a very considerable portion of the light from the auxiliary source, that is intercepted by the reflector, into an area substantially immediately in front of the car where it will be useful in illuminating the curbs, side ditches, crossroads, etc. However, a very considerable portion of the direct light from the auxiliary source will be thrown toward the opposite side of the road, so as to be available for reading road signs and useful in illuminating the front portion and fenders of an approaching car.
- 25 To insure a sufficient quantity of light for these purposes the filament 28 of the auxiliary source of light should be placed out beyond the plane of the edge of the reflector, as is shown in Figure 1.
- 30 While any suitable lens can be used as a part of my improved headlight, I prefer to make use of the bowl-shaped lens 29, shown in Figure 1, having the outwardly convexed central portion 30 and the marginal flange 31 that extends substantially parallel with the axis of the reflector and which preferably embodies a slight prism having the ability to direct light somewhat to the rear of the headlight. It will be noted that the lamp 27 extends into the lens and is enclosed on some of its sides by the marginal flange 31 of the lens. This permits the direct light from the auxiliary source easily to pass through the lens in a lateral direction.
- 35 40 45 50 By placing the two sources of light as shown in Figure 1, that is, one well inside of the plane of the edge of the reflector and one outside of this plane, I make it possible to use considerably more than half of the light emitted from the main source in producing the main beam of light used for illuminating the roadway and objects far in advance of the vehicle, and to use considerably more than half of the light emitted from the auxiliary source in illuminating the sides of the road and that portion of the road immediately in advance of the vehicle by means of the direct light from the auxiliary source.
- 55 The main source of light should, of course, be placed adjacent the focal point, or focal region, of the reflector, but I prefer to locate it somewhat below the focal point because in this manner the upper portion of the beam is directed downwardly toward the axis of the reflector so as to prevent light rays of undue intensity interfering with the vision of an approaching driver. This effect can be, and is preferably, increased by tilting the top of the reflector forwardly and downwardly, as is indicated in dotted outline in Figure 1.
- 60 65 70 75 It will, of course, be understood that the wiring and switching arrangements for the two sources of light may be such that either may be operated separately, or both of them can be operated at the same time. Preferably, the auxiliary source of light will have a candle power somewhat less than that of the main source of light.
- 80 85 90 95 While I have described the details of construction of the preferred embodiment of my invention, it is to be clearly understood that my invention is not limited to these details but is capable of other adaptations and modifications within the scope of the appended claim.
- Having thus described my invention, what I claim is:
- A headlight for illuminating the sides of the roadway and projecting a beam of light longitudinally thereof, comprising a reflector having a focal point lying well within the plane of the edge thereof, a main source of light adjacent said focal point, an auxiliary source of light supported by said reflector adjacent the side edge and close to the axial horizontal plane thereof, and a lens for said reflector having a marginal cylindrical flange extending thereabout, said auxiliary source of light being positioned outside of the plane of the edge of the reflector whereby light from said auxiliary source may pass through said cylindrical flange illuminating the sides of the road.
- 100 105 In witness whereof I hereunto subscribe my name, this 1st day of March, 1926.

WALTER D'ARCY RYAN.
